CLAIM

The ornamental design for a glove having a mount for mounting a cell phone to the wearer's hand, as shown and described.

DESCRIPTION

FIG. 1 is an isometric view of a glove having a mount for mounting a cell phone to the wearer's hand, showing my new design.

FIG. 2 is a right side view of the design of FIG. 1.

FIG. 3 is a left side view thereof.

FIG. 4 is a front end view thereof.

FIG. 5 is a rear end view thereof.

FIG. 6 is a top view thereof; and,

FIG. 7 is a bottom view thereof.
